FIG. 1 is a perspective view taken from the left front side of a combined handle and lock housing set embodying my invention, shown mounted on a door;

FIG. 2 is an enlarged view taken as indicated by the lines and arrows 2—2 in FIG. 1 showing the right side of the embodiment shown in FIG. 1;

FIG. 3 is an enlarged rear view of the embodiment shown in FIG. 1;

FIG. 4 is a greatly enlarged section taken as indicated by the lines and arrows 4—4 in FIG. 2;

FIG. 5 is a top view taken as indicated by the lines and arrows 5—5 in FIG. 3;

FIG. 6 is a bottom view taken as indicated by the lines and arrows 6—6 in FIG. 3;

FIG. 7 is a view taken as indicated by the lines and arrows 7—7 in FIG. 3;

FIG. 8 is a perspective view taken from the left front side of another combined door handle and lock housing set embodying my invention, shown mounted on a door;

FIG. 9 is an enlarged right side view taken as indicated by the lines and arrows 9—9 in FIG. 8;

FIG. 10 is an enlarged rear elevation of the embodiment shown in FIG. 8;

FIG. 11 is a top view taken as indicated by the lines and arrows 11—11 in FIG. 10; and

FIG. 12 is a bottom view taken as indicated by the lines and arrows 12—12 in FIG. 10.

This application incorporates by reference my prior pending applications Ser. No. D. 20,194, filed Nov. 20, 1969, and Ser. No. D. 20,029, filed Nov. 10, 1969, now abandoned, and discloses and claims, in part, subject matter disclosed and claimed therein.

The shading employed does not connote actual appearance, but is an expedient to best illustrate shape.

The door shown in phantom lines forms no part of the design and has been included for purposes of illustrating the environment only.

Portions have been foreshortened on the drawings for convenience of illustration.

The front view of each embodiment is identical to the rear view of that embodiment.

I claim:

The ornamental design for a combined door handle and lock housing set, as shown and described.
